UNITED STATES PATENT OFFICE.

JOHN W. BUTLER, OF NEW BRITAIN, ASSIGNOR TO THE BRADLEY & HUB-BARD MANUFACTURING COMPANY, OF MERIDEN, CONNECTICUT.

CALL-BELL.

SPECIFICATION forming part of Letters Patent No. 247,610, dated September 27, 1881.

Application filed August 13, 1881. (No model.)

To all whom it may concern:

Be it known that I, JOHN W. BUTLER, of New Britain, in the county of Hartford and State of Connecticut, have invented a new Improvement in Call-Bells; and I do hereby declare the following, when taken in connection with the accompanying drawings and the letters of reference marked thereon, to be a full, clear, and exact description of the same, and which said drawings constitute part of this specification, and represent, in—

Figure 1, a sectional side view; Fig. 2, perspective view of the hammer-holder detached; Fig. 3, perspective view of the hammer; Figs. 4 and 5, modifications.

This invention relates to an improvement in that class of call-bells commonly called "pressure-bells"—that is to say, such as have the bell hung upon a post with the spindle down through the bell, in connection with the hammer within the bell, so that pressing down the spindle will force the hammer to strike the bell; then, when released, the hammer falling raises the spindle. In the usual construction the hammer is hung between two ears on the post, the ears and the shank of the hammer drilled to receive a wire pivot.

The object of this invention is to avoid the drilling of the ears and insertion of the pivot, whereby the difficulty above referred to is prevented; and it consists in constructing the post with an open bearing or seat which will receive a corresponding part of the hammer and support the hammer entirely without the interposition of the usual wire pivot, as more fully hereinafter described.

A represents the base, and B the post which rises within the bell C, and on which the bell rests, and there secured by the tip D, extending through an opening in the bell and screwed into the post, as shown in Fig. 1, and in the usual manner.

The post B is constructed with two hook-shaped projections, *aa*, corresponding in position substantially to the usual ears, the mouth or open side of the hook upward toward the bell.

The hammer-shank E is constructed with the usual arm, F, upon which the spindle G acts in the usual manner. At the upper end of the shank transverse trunnions *b* are con-

structed to set upon the open bearings *a a*, the shank hanging between the said bearings, the bearings forming seats for the trunnions, and on which the hammer will freely swing. The hammer is hung in its position before the bell is set upon the post; then when the bell is in place it covers the open bearings, so as to prevent the possibility of displacement of the hammer.

Instead of forming the open bearing hook-shaped and trunnions *b b* on the hammer, the projecting arms may be connected by a bar, *d*; (see Figs. 4 and 5;) and the hammer, instead of the trunnions, is made with a hook shape, as *e*, this being simply the reverse of the construction first described, and so that the hammer is hung by the hook *e* upon the bar *d*, as seen in Fig. 4, and from which it cannot be removed after the bell is in place, because the hammer cannot be raised sufficiently high to do so without coming in contact with the bell.

While I prefer the first-described construction, it will be readily seen that the reverse, as shown in Figs. 4 and 5, is an equivalent therefor. In either case there is the same open seat or bearing and corresponding part to rest thereon, so that the usual drilling and pivot will be avoided.

While the bell itself is all that is required to hold the tongue in its seat—that is to say, will prevent its detachment therefrom—the ends of the hooked-shaped projections *a a* may be bent over the trunnions *b b*, or, which is the same thing, the hook of the hammer bent over the bar, which would secure the hammer in place independent of the bell; but in that case it would be the open bearing on the post and corresponding part of the hammer, to rest thereon, which constitutes the essential feature of my invention.

I claim—

In that class of call-bells known as "pressure-bells," the post constructed with an open bearing, and the hammer constructed with a corresponding part, to rest on said open seat, substantially as described.

JOHN W. BUTLER.
